UNITED STATES PATENT OFFICE.

JOHN R. MULLIN, OF ROME, NEW YORK, ASSIGNOR OF ONE-HALF TO JOHN F. HOLZINGER, OF NEW YORK, N. Y.

NON-REFILLABLE BOTTLE.

1,028,077.

Specification of Letters Patent. Patented May 28, 1912.

Application filed November 9, 1911. Serial No. 659,402.

To all whom it may concern:

Be it known that I, JOHN R. MULLIN, a citizen of the United States, residing at Rome, in the county of Oneida and State of New York, have invented certain new and useful Improvements in Non-Refillable Bottles; and I do hereby declare the following to be a full, clear, and exact description of the invention, such as will enable others skilled in the art to which it appertains to make and use the same.

My invention relates to new and useful improvements in receptacles and more particularly to non-refillable bottles.

15 The object of my invention is to provide a bottle of cheap construction having means disposed in its discharge opening which will allow the contents of the bottle to flow therefrom, but will prevent the refilling of the 20 bottle.

A further object of my invention is to provide a mechanism to prevent the refilling of a bottle, which may be constructed of cheap material such as glass.

25 Other objects and advantages of my invention will be hereinafter clearly made apparent in the specification and pointed out in the claim appended thereto.

In the accompanying drawing I have 30 shown the preferred embodiment of my invention.

In said drawing, Figure 1 is a vertical sectional view through a portion of a bottle having my improved form of non-refilling 35 attachment secured thereto. Fig. 2 is a transverse sectional view as seen on line 2—2, Fig. 1, looking in the direction of the arrow, and, Fig. 3 is a transverse sectional view as seen on line 3—3, Fig. 1, looking in the direction of the arrows.

40 Referring to the drawings by numerals of reference, similar reference numerals designating similar parts throughout the several views, 1 is the body of the bottle or other receptacle, which may be formed of glass or other desired material and is provided with an outlet or neck 2. The opening between the outlet 2 and the body portion 1 of the receptacle is restricted, as shown at 3, to 45 form a seat for a ball valve 4, which normally closes said opening to prevent a liquid or other substance from being poured into the receptacle.

The ball valve 4 is preferably provided 50 with a counterweight 5, secured thereto by

means of a rigid curved shank 6, which holds said valve in closed position until the receptacle has been tilted to a considerable degree. The guard disk 7 is disposed in the neck 2 so as to normally rest upon the upper 60 surface of the ball valve 4. The lower surface of the guard disk 7 is preferably concaved in order that the ball valve and guard disk will occupy a minimum space. The guard disk is of less diameter than the inner 65 diameter of the outlet opening and the edges of said disk are preferably provided with a plurality of ribs 8, which space the edge of the disk from the inner surface of the outlet opening, thus allowing the contents of the 70 receptacle to readily flow around the disk, when desired.

A short distance below the upper surface of the guard disk 7 the outlet opening is slightly enlarged so as to form a shoulder 75 9, against which is seated a cap 10, which is adapted to snugly fit in the outlet opening. The cap 10 is provided with a central aperture 11, through which the contents of the receptacle may flow when said receptacle is 80 tilted. The bottom of the cap is preferably provided with a plurality of lugs 12 to prevent the guard disk 7 from falling thereagainst and closing the aperture 11.

A plurality of springs 13 have one end 85 seated in the periphery of the cap, the free ends of said springs extending upwardly and outwardly. The cap 10 is suitably cut away so that the free ends of the springs may be depressed flush with the periphery 90 of the cap. The inner surface of the outlet opening is provided with a circumferential groove 14, or a plurality of depressions, adapted to receive the free ends of said springs when the cap is inserted in the outlet opening and forced therein against the shoulder 9. When the cap has been thus positioned the free ends of the springs will extend into the groove or depressions 14 and effectively prevent the removal of said cap. 100 When desired the outer end of the outlet may be sealed with the usual form of cork 15, or other desired closure.

From the foregoing description it will be seen that I have provided a device which will effectively prevent the refilling of the receptacle. It will further be seen that all the parts of my device, except the springs, may be formed of glass or other desired cheap material. It will further be seen that when 110

the parts of the device are once placed in operative position, it will be impossible to remove the same or to tamper with the operation thereof in any manner.

5 What I claim as new is:

A non-refillable bottle comprising a receptacle, an outlet therefor, a valve seat formed at the junction of the body of said receptacle and said outlet, a ball valve normally seated thereagainst and having a depending counterweight, a cap snugly fitted within said outlet, said cap having a central aperture and lugs upon the under face there-

of, a cylindrical guard disk of greater diameter than said valve disposed between 15 said cap and valve and having the top and bottom faces thereof concaved, the edges thereof being tapered from top to bottom and provided with ribs.

In testimony whereof I have signed my 20 name to this specification in the presence of two subscribing witnesses.

JOHN R. MULLIN.
